UNITED STATES PATENT OFFICE.

RIAL T. ROLFE, DECEASED, LATE OF HARVEY, ILLINOIS, BY OLIVE ROLFE, EXECUTRIX, OF HARVEY, ILLINOIS, ASSIGNOR TO ROLFE IRON COMPANY, OF CHICAGO, ILLINOIS, A CORPORATION OF ILLINOIS.

ADJUSTABLE GATE.

Application filed July 14, 1921. Serial No. 484,810.

To all whom it may concern:

Be it known that RIAL T. ROLFE, deceased, late a citizen of the United States, and a resident of Harvey, in the county of 5 Cook and State of Illinois, has invented certain new and useful Improvements in an Adjustable Gate, of which the following is a specification.

This invention relates to gates, and pertains particularly to improvements in the construction of roadway gates designed to be pivotally supported at one end for horizontal swinging movement.

The manufacturer who would undertake 15 the production of gates in quantities for commercial distribution encounters many problems which are not evident to the average person, and which are not encountered by a workman skilled in the art who has 20 beforehand knowledge of the particular conditions obtaining in each instance in which he may be called upon to supply a gate. In the first place, the manufacturer of gates on a commercial scale for general distribution is 25 met with the consideration of producing an article which may be sold at a sufficiently low price to make it profitable to a purchaser to buy the same rather than build it himself with such materials and labor as he 30 may have available, and by which means he himself ordinarily can produce it at a very small cost. In the second place, the manufacturer of such gates must provide a structure 35 which will satisfactorily meet a great variety of conditions under which the gate must be installed and used, such conditions varying as between different installations, and varying also in each particular installation, over a space of time. For example, 40 he must provide a gate which is adapted for installation on roadways where the elevation between the fence portions at opposite sides of the roadway varies, and also where the post on which the gate is hinged may be expected to change under the weight of the 45 gate and pressures induced by its use.

The general purpose of the present invention is the production of a gate structure which will admit of construction at a very 50 low initial cost, and which is adaptable as nearly as possible to all the varying conditions of installation and use.

More specifically, the various objects of the invention comprise the production of a

gate which may be largely constructed, particularly as to the frame, out of re-claimed material, such as discarded boiler tubes, which may be fabricated and assembled by simple and inexpensive operations, and which includes features whereby the frame 55 members may be relatively adjusted so as to vary their angular relationship to accommodate the gate to different inclinations, and provide for the requisite extent of adjustments and at the same time contribute the 60 necessary strength and stability in the connections to constitute a durable and strong 65 structure requisite to withstand the usage to which it is subjected.

Other objects of the invention will be 70 pointed out hereinafter, will be obvious from the following disclosure, or indicated in the appended claims, reference being had to the drawings forming a part of this specification in which an illustrative embodiment 75 is shown, it being understood that the scope of the invention includes similar constructions varying in particulars from the form shown.

In the said drawing,

Fig. 1 is an elevational view of the gate embodying my invention;

Fig. 2 is a detail illustrating in top view the connection between the posts and the rails of the frame; and

Fig. 3 is a detail of the stay-adjusting and retaining means.

Referring to these drawings by means of the reference numerals applied, let it be understood that the numeral 1 designates a 90 post upon which the gate may be hinged and numeral 2 designates a cooperating post upon which the gate may be latched. The gate itself includes the end posts 4, the top rail 5 and the bottom rail 6. These members 95 preferably are formed of tubing, an economical sort of which is discarded boiler tubes properly treated to resist weathering. For forming the connection between the rails and the posts, straight tubes of suitable length are split longitudinally at their ends for a short distance, the several portions being straightened in parallel relationship to form cooperating arms 7 having their facing surfaces spaced apart substantially the external diameter of the post member with which they are to cooperate. Disposed in contact with the outer sides of the 100

arms 7 and the adjacent integral portion of the tube are similarly formed connection members 8 having curved parts adapted to embrace the tube closely and parts adapted 5 to lie in close contact with the flat arms 7 and the curved parts joining them to the integral tube. These connection members are secured to the tube by any easily assembled means such as through-bolts 9, in such 10 fashion that they are supported rigidly thereon. The arms 7 and overlying portions of the connection members 8 are oppositely apertured for the reception of a pivot bolt 10 designed to pass through the post member 15 when the latter is interposed between the arms 7. In the slotting and shaping of the tube to provide the arms 7, the bifurcation is of sufficient extent to allow for a considerable change of angularity between the 20 post 4 and the rail tube as they may be moved relatively on the pivot afforded by the bolt 10, and the form and extent of the arms 7 are such that substantial bearing contact is afforded between them and the side of 25 the post on opposite sides of the pivot bolt, in all angular positions of the post and rail. The four connections between the posts and rails being formed in this fashion, very substantial but flexible joints are provided, 30 which will permit of the necessary change of angularity of said members in the plane of the structure, and at the same time retain the parts substantially against twisting or deflection out of that plane. By means of 35 the connection members 8 the material in the arms 7 is effectively supported against twisting, and because of the substantial longitudinal bearing contact between the curved portions of said members and the shaft of the 40 rail, the arms 7 are relieved of half of the weight of the supported portions of the structure, such weight being transmitted directly from the bolt to the integral portion of the tubing.

45 This articulated assembly of the posts and rails permits of the adjustment of the gate relative to the hinge post to accommodate it to a lateral slope of the roadway in either direction, or to variations of the supporting post from the vertical. This is important in maintaining the proper limitation of clearance between the bottom of the gate and the roadway to permit it to operate as an effective bar to the passage of animals under it. The space between the posts may be suitably barred by stringing wires or flexible mesh fencing material 11 from the frame members, and one or more transverse stays or struts 12 may be pivotally connected to 50 opposite frame members to maintain their parallelism and serve to support the flexible wires.

55 For the purpose of sustaining the frame members in the desired angular relationship, 60 one or more diagonal stay members 14 may

be provided, anchored at the upper end to the hinge post, and extending diagonally to the lower rail or to the lower portion of the latch post. In the form illustrated a transverse stay member in the form of a rod or 70 heavy gauge wire is shown, the same carrying a short chain 15 at one end, which chain is arranged in cooperation with a suitable keeper 16 pivotally mounted on the frame member. As illustrated in Fig. 3, this keeper 75 may be in the form of a slotted plate or link affording an aperture 16^a adapted to permit the passage of the chain links, and merging into a slot 16^b adapted to accommodate the thickness of the links but not their width. 80 The chain may be drawn through the aperture 16^a of the keeper to the desired extent and engaged in the slot 16^b as illustrated in Fig. 3, thereby serving with the diagonal stay member to support the free end of the 85 gate at the desired elevation or angularity relative to the hinge post, which disposal may be changed as desired by shifting other links of the chain into the effective engagement with the keeper. The pivotal mounting of the keeper accommodates the change 90 of angularity of the frame member upon which it is mounted relative to the hinge post.

95 The gate may be mounted for horizontal swinging movement in any suitable fashion, a convenient means being provided by substantial eye-bolts 17 strung onto the hinge post, the upper one engaging a collar or flange 18 thereon to limit downward movement of the post. Any suitable latch 19 may be arranged for retention of the free end of the gate.

100 The structure may be shipped in compact disassembled form by rolling the fabric about the disconnected post members and securing the rail members and stays in parallel relationship therewith. A gate constructed in the fashion above described fulfills the contemplated commercial requirements in that it may be manufactured very 105 cheaply, and may be quickly assembled at the place of installation by simply seating the pivot bolts 10, bolting up the stay members 12, and forming the desired connections 110 between the wire mesh and the rail members. The assembled structure is very stable due to the substantial bearing areas provided by the connections between the posts and rails, and the great variety of conditions which 115 gates are required to meet are accommodated by the range of adjustability afforded.

120 I claim:

1. A gate construction including post members and tubular rail members, the latter having their ends bifurcated to form parallel arms engaging opposite sides of the post members, connection members having parts embracing tubular portions of the rails and parallel portions overlying and contact- 125 130

ing said parallel arms, fastening means rigidly connecting the connection members to said tubular portions of the rail members and pivot bolts seated in the post members and passing through the parallel arms and the overlying portions of the connection members, said bolts serving as connections for the rail and post members and cooperating with said fastening means to maintain 10 the connection members in contact with the parallel arms of the rail members.

2. In a gate construction, post members and tubular rail members, the latter having bifurcated ends shaped to form parallel 15 arms engaging opposite sides of the post members, connection members having curved portions embracing tubular portions of the rail members and flat portions overlying and contacting said parallel arms, fastening 20 means cooperating with said curved portions

to maintain the connection members rigidly in alignment on the rail members, pivot bolts seated in the post members and passing through said parallel arms and connection members whereby the rail members are supported on the post through the connection members and the parallel arms, said pivot bolts cooperating with the fastening means to maintain the connection members in alignment and lateral contact with the parallel 25 30 arms.

In testimony whereof I have hereunto signed my name in the presence of two subscribing witnesses.

OLIVE ROLFE,
*Executrix of the Estate of Rial T. Rolfe,
deceased.*
